UNITED STATES PATENT OFFICE.

WILLIAM PICK, OF SCRANTON, PENNSYLVANIA.

CIRCUIT-CONTROLLING TELEPHONE-RECEIVER SUPPORT.

1,287,421.

Specification of Letters Patent. Patented Dec. 10, 1918.

Application filed November 7, 1914, Serial No. 870,795. Renewed April 24, 1918. Serial No. 230,607.

To all whom it may concern:

Be it known that I, WILLIAM PICK, a subject of the Emperor of Austria and Apostolic King of Hungary, residing at Scranton, in the county of Lackawanna and State of Pennsylvania, have invented certain new and useful Improvements in Circuit-Controlling Telephone-Receiver Supports; and I do hereby declare the following to be a full, clear, and exact description of the invention, such as will enable others skilled in the art to which it appertains to make and use the same.

My invention relates to an extension support for telephone receivers, of such character that normally, or when the support is in the collapsed position, the main line or talking circuit, is broken, but when the support is extended, the last named circuit is closed. This extension support is of such character that it maintains the receiver in the proper elevated position for use without the aid of the hand of the user, thus giving the latter the use of both hands during a telephone conversation.

As illustrated in the drawing, the extension support is of the lazy tongs type, but it must be understood that other forms of support which are adapted to be alternately extended and collapsed, may be employed without departing from the spirit of the invention.

One object of my invention is to provide a receiver support which shall obviate the requirement that the user of the telephone shall remove the receiver from the hook preparatory to beginning a conversation, and restore the receiver to the hook after the conversation is completed. Still another object, as heretofore intimated, is to obviate the requirement that the user shall hold the receiver in his hand during the conversation.

These advantages, which are incident to my improved construction, will greatly facilitate the ease and rapidity of telephonic communication, as will be readily understood, and the invention is therefore be-

lieved to be important both to the telephone company and to the subscribers.

Having briefly outlined my improved construction, I will proceed to describe the same in detail, reference being made to the accompanying drawing, in which is illustrated an embodiment thereof. In this drawing,—

Fig. 1 is a side elevation of a telephone equipped with my improvement.

Fig. 2 is a section taken through the standard and also cutting the tubular extension carrying the circuit make-and-break device of my improvement. This is a front view with the transmitter shown in elevation, the section being taken on the line 2—2, Fig. 1.

Fig. 3 is a similar view with the extension support shown in place upon the tubular extension. This may be considered a view looking in the direction of arrow 3, Fig. 1.

Fig. 4 is a top plan view of the telephone equipped with my improvement, or a view looking in the direction of arrow 4, Fig. 1, the construction being shown partly in horizontal section taken on the line 4—5, Fig. 3.

Fig. 5 is a similar view, with the extension support mostly broken away, but showing the make-and-break device in position for closing the talking or line circuit.

The same reference characters indicate the same parts in all the views.

Let the numeral 5 designate the standard of the telephone upon which the transmitter 6 is mounted in the usual manner, this standard having the conventional base 7 broken only by an opening 8 covered by a transparent device and through which an indicating or signal light 9 may be viewed, the use of which will be hereinafter more fully explained.

Within the standard 5, which is hollow for the purpose, are located three spring contacts respectively designated by the numerals 10, 11 and 12. These contacts are mounted upon an upright metallic plate 13 and are insulated therefrom and from each other by insulated layers, respectively desig-

nated 14, 15 and 16. From the contact 10, a conductor 17 leads to the signal lamp 9 from which a second conductor 18 leads to the central station, or source of current supplied, this conductor being one member of the line or talking circuit. From the central station, the other member 19 of the line circuit leads to a point 20 from which one conductor 21 leads to the transmitter 6, while another conductor 22 leads from the same point 20 to the receiver 23. From the transmitter, a conductor 24 leads to the spring contact 12, which contact, when in its normal position, or when the telephone is not in use for conversation purposes, is electrically connected with the metallic plate or contact support 13, through the medium of a metallic spacing block 25, which is mounted on the said rod, whereby the ringing circuit is normally completed through the said plate, a screw 26 at the bottom of the base, a conductor 27, a signal bell 28 and a conductor 29, to the ground, as shown at 30. From the contact 11, a conductor 31 leads to the receiver, the conductor 22 being the companion conductor, and connected with the receiver, as heretofore explained. The two conductors 22 and 31 leave the hollow standard through an opening 32, whence they pass into a laterally disposed tubular member 33, and out through an opening 34 formed in said member. Upon the upper extremity of the hollow standard 5 is formed an exteriorly projecting interiorly threaded collar 35, forming a socket into which is screwed the inner extremity of the tubular device 33, in which is slidably supported, a plunger 36, the latter being mounted upon a block 37 secured to the device 33 and provided with a layer 38 of insulating material, which insulates the said plunger from the part 33. This plunger is secured by means of a set screw 39 which passes through an elongated opening 40 formed in the plunger, the screw entering the insulating material 38 and so adjusted that the plunger may be moved back and forth upon its insulating support with freedom. Upon this plunger is mounted and made fast a stop collar 41 which engages one extremity of a spiral spring 42 which surrounds the inner portion 43 of the plunger, the opposite extremity of the spring engaging the insulating washer 44 which rests against the wall 55 of the standard around an opening 45, through which the part 43 of the plunger passes, the inner extremity of the plunger being normally located within the upper portion of the hollow standard 5 and registers with the perforation 45 formed in the rod or upright member 13. The spring 42 normally holds the plunger in the position shown in Fig. 3, or out of engagement with the spring contact 12, the upper portion of the latter,

however, being in position to be acted upon by the plunger when the latter is forced through the perforation 45, as hereinafter explained.

The opposite or outer extremity of the plunger is beveled as shown at 46, whereby it is adapted to engage the inner conical portion 47 of an insulating plug 48, which is movable in an opening 49 formed in one side of the device 33. The body portion of this plug is cylindrical. Beyond the cone-shaped part 47 and leading from the smaller extremity thereof, is a threaded part or screw 50, which enters the inner end of a bracket 51, the inner extremity of this bracket being slideable in an opening 52 formed in the device 33, directly opposite the opening 49. Connected with the outer extremity of the bracket 51 as shown at 53, is a lazy tongs structure 54, to the outer extremity of which is secured a bracket 55 to which is made fast the receiver 23 by means of a screw 57 which passes through a lug 58 of the bracket and spaced ears 49 of the receiver, the connected parts having registering perforations and the screw being fastened by a nut 59.

As this lazy tongs member is of the usual construction, it is unnecessary to describe the same with particularity or in detail, as it will be readily understood that the joints designated by the numeral 60 are all pivotal, thus making it practicable to extend and collapse the receiver support at will, or throw the same from the dotted line position in Fig. 1, to the full line position in the same figure, or vice versa, as may be required.

To facilitate the support of the conductors 22 and 31, between the telephone standard and the receiver, the lazy tongs structure is provided with eyes 61 through which the conductors pass.

From the foregoing description, the use and operation of my improvement will be readily understood. Assuming that the support is in the collapsed position as shown in full lines in Figs. 3 and 4 and in dotted lines in Fig. 1, it will be understood that the line or talking circuit is broken, as this circuit must be completed through the conductor 17, which leads to the spring contact 10, and the last named contact is insulated in such a manner as to break the circuit, as best illustrated in Fig. 3. Now, if it is desired to hold a conversation, the user will grasp the receiver, and move the same toward him, until the support therefor, being mainly the lazy tongs member 54, is extended to the position shown in full lines in Fig. 1. During such extension, the lazy tongs member 54 is not only extended, but the plug 48 and the bracket 51 are moved in the tubular device 33, in the direction of the travel of the receiver. This movement is sufficient to cause the cone-shaped frustum

part 47 of the plug to act upon the beveled extremity 46 of the plunger 36, and will force the plunger against the action of its spring 42, into engagement with the contact 12, whereby the latter is disengaged from the spacing member 25 and brought into engagement with the companion contact 10, as best illustrated in Fig. 2 of the drawing. In this event, the talking or line circuit will be completed and the ringing circuit broken. For instance, the line or talking circuit may be traced through the conductor 19, to the point 20, thence through the conductor 22 to the receiver, and thence from the receiver through the conductor 31, the spring contact 11, the spring contact 12, and the conductor 24, to the transmitter 6, and thence from the transmitter through the conductor 21 and the conductor 19. At the same time, the circuit is completed through the signal lamp 9, through the medium of the spring contact 10, the conductor 17, which is connected with the lamp, and the main line conductor 18. Again, when the talking circuit is closed as heretofore described, the ringing circuit is broken, as this circuit can only be completed through the medium of the spring contact 12 when in engagement with the contact block 25, as heretofore explained.

When the receiver is in the extended position, as just explained, it is supported by the lazy tongs structure in such a manner that the user may place his ear thereto and hear the message, without the necessity of using the hand for supporting the receiver, thus leaving both hands free for other use. Now, when the conversation is completed, the receiver may be moved toward the telephone standard, whereby the lazy tongs member is thrown into the collapsed position, and the bracket 51 and plug 48 actuated to return them to their normal position, thus leaving the plunger 36 free to return to its normal position, due to the influence of its spring 42, whereby the talking or line circuit is broken and the ringing circuit completed. At the same time, the circuit is broken through the signal light 9, which serves to assure the user of the telephone that the talking or line circuit is closed or broken, as the case may be.

The support for the receiver may be reversible, that is to say, changed from one side to the other of the telephone instrument, by simply turning the tubular device 33 in its socket, whereby, the plug 48 and its attachments will be thrown to the dotted line position at the left of Fig. 1. This may be accomplished by loosening a lock nut 65 which is applied to the threaded part of the device 33, and is adapted to screw against the collar 35 in order to lock the said device and the support for the receiver in the de-

sired position of adjustment. By reason 65 of this construction, it becomes practicable to place the receiver in position to be heard through either ear of the user. It sometimes happens that people are deaf in one ear and if it should be the left ear, the ordinary arrangement of the receiver for hearing through the left ear would not be satisfactory. Such persons may therefore reverse the position of the receiver, or throw it to the opposite side of the instrument 70 from where it is usually located. The receiver will then be in the proper position to permit the customer to receive the message through the right ear. In this event, the transmitter 6 must be thrown to a corresponding position, or to the dotted line 75 position indicated at the left of Fig. 1.

Having thus described my invention, what I claim is:—

1. The combination with a transmitter 85 support, and a plurality of contact springs normally insulated from each other inclosed therein, a hollow support secured to said transmitter support, a receiver, an extensible support for said receiver mounted on 90 said hollow support and means for forcing said contact springs into contact mounted in said hollow support and operated by said extensible support.

2. The combination with a transmitter 95 support, and a plurality of contact springs normally insulated from each other inclosed therein, a plunger adapted to move said springs into contact, a plug for moving said plunger in one direction, a spring for moving 100 said plunger in the opposite direction, a lazy tongs having one end connected to said plug and a receiver supported by the other end of said lazy tongs.

3. The combination with a transmitter 105 support, of a collar secured to said support, a hollow support adjustably secured in said collar, a lazy tongs supported at one end by said hollow support, and a receiver attached to the other end of said lazy tongs. 110

4. The combination with a transmitter support, of a collar secured to said support, a hollow support adjustably secured in said collar, a lazy tongs supported at one end by said hollow support, a receiver attached 115 to the other end of said lazy tongs, a plurality of contact springs mounted in said transmitter support, and means operated by the movement of said receiver for moving said springs into and out of contact. 120

5. The combination with a transmitter support of a lamp mounted in the base thereof, a lazy tongs supported at one end by said support, a receiver supported by the other end of said lazy tongs, an electric 125 circuit, and means for opening and closing said circuit through said lamp operated by the movement of said receiver.

6. The combination with a transmitter support of a lamp mounted in the base thereof, a lazy tongs supported at one end by said support, a receiver supported by the other end of said lazy tongs, a talking circuit including said lamp whereby said lamp indicates when said circuit is closed, and

means for closing said talking circuit when said lazy tongs is extended and for opening said talking circuit when said lazy tongs is contracted.

In testimony whereof I affix my signature.

WILLIAM PICK.
